GAS BURNER WITH SECONDARY
AIR FEED

Carlton M. Wheelock, Milwaukee, Wis.

Application January 9, 1947, Serial No. 720,996

9 Claims. (Cl. 158—116)

1

This invention relates to gas burners and chiefly concerns gas burners of the type having a continuous discharge port extending about the periphery of the burner head from which gas issues to burn in a flame extending uninterruptedly about the edge portion of the burner.

It is a general object of this invention to provide an improved gas burner of the character described.

More specifically this invention has as its object the provision of a gas burner of the character described having greatly increased port area as compared with conventional burners of the continuous port type.

Another object of this invention resides in the provision of a gas burner of the character described with substantially ring-like ports spaced from one another around the periphery of the burner head from which gas issues to burn in a flame hollow at its base.

Still another object of this invention resides in the provision of a gas burner with a series of substantially ring-like ports spaced around the periphery of the burner head and from which gas issues to burn in a flame hollow at its base wherein means is provided for supplying secondary combustion air to the hollow bases of said flames.

A further object of this invention resides in the provision of substantially ring-like ports for a gas burner of the character described connected with one another by narrow slit like ports so as to produce a continuous port arrangement of substantial area extending about the entire periphery of the burner head.

Another object of this invention resides in the provision of a gas burner of the character described which readily lends itself to fabrication from stampings for low cost production.

Another object of this invention resides in the provision of a gas burner of the character described having improved means for assuring substantially uniform distribution of fuel to all of the ported areas of the burner.

In this respect it is a further object of this invention to assure uniform distribution of fuel to the peripheral port arrangement of the burner by means of a series of circumferentially spaced expansion chambers located near the periphery of the burner head, and by supplying fuel to certain of said expansion chambers from a central zone of the head while supplying fuel directly to one of said expansion chambers from a point adjacent to the periphery of the head.

With the above and other objects in view, which will appear as the description proceeds, this in-

2

vention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiment of the invention constructed according to the best modes so far devised for the practical application of the principles thereof, and in which:

Figure 1 is a plan view of the gas burner of this invention with parts thereof broken away and shown in section;

Figure 2 is a longitudinal sectional view taken through Figure 1 along the plane of the line 2—2;

Figure 3 is an enlarged detail sectional view taken along the line 3—3 of Figure 1;

Figure 4 is a plan view of a modified type of burner;

Figure 5 is a longitudinal sectional view of the burner of Figure 4 taken along the plane of the line 5—5;

Figure 5a is an enlarged detail sectional view taken along the line 5a—5a of Figure 4;

Figure 6 is a cross sectional view through the manifold tube of the burner and taken along the line 6—6 of Figure 5; and

Figure 7 is an enlarged fragmentary sectional view illustrating a still further modified form of the invention.

Referring now more particularly to the accompanying drawings, the numeral 5 generally designates the gas burner of this invention. The burner 5 comprises a substantially flat and nearly circular hollow head 6 including spaced apart upper and lower disc-like head forming members 7 and 8, respectively, and a rim-like flange 9 extending between the peripheral edge portions of the upper and lower head forming members but carried by the lower head forming member 8.

The upper and lower head forming members 7 and 8 are connected together in spaced apart relationship by means of upright tubular necks 10 defining cored holes 11 extending vertically through the burner head. In the present embodiment of the invention the head is shown with three such tubular necks providing three cored holes spaced substantially equal distances from one another about a central zone of the head and lying close to the peripheral rim-like portions 12 of the head.

The three tubular necks 10 cooperate with one another to define in effect a hollow hub-like por-

55

tion 13 at the central zone of the head and spoke-like hollow passages 14 between adjacent necks. It will be noted that the spoke-like passages 14 are substantially restricted but that the same lead to expansion chambers 15 adjacent to the junctions of the spoke-like portions of the upper and lower head forming members with the rim 12 of the head and communicating with the hollow interior of the rim which likewise defines a restricted passageway extending entirely about the periphery of the head.

The lower head forming member 8 has one of its spoke forming sections depressed outwardly as at 16 from a point adjacent to the innermost wall of one of the tubular necks 10 rearwardly from said neck beneath the central zone 13 of the head and continued on between the remaining two necks toward the rear periphery of the rim 12.

The depressed portion 16 actually provides an inward extension of a manifold tube 18 joined to the rim 12 at the rear periphery of the head with the upper portion of the manifold tube connecting with the flange 9 and the lower portion of the tube in line with and forming a part of said depressed spoke forming portion 16.

It will be obvious, of course, that the flange 9 of the rim is apertured so that the manifold tube has its interior directly communicated with the expansion chamber 15 at the rear of the head so that said chamber receives gas flowing along the upper portions of the tube while the gas flowing along the lower portions of the tube may pass beneath the expansion chamber and be discharged directly into the central zone of the head at its hollow hub-like portion 13.

From Figure 2 it will be apparent also that the center line of the manifold tube 18 lies substantially in the plane of the lower head forming member 8 and that the upper portion of the tube is spaced slightly beneath the upper head forming member 7.

A combustible gaseous mixture flowing through the tube toward the head from the inlet of the tube, as stated previously, initially enters the hollow interior of the head at the expansion chamber 15 alongside the rear periphery of the head to be expanded upwardly and laterally therein to opposite sides of the tube axis into the substantially restricted passage formed by the hollow interior of the rim 12 and leading between the two rearmost tubular necks 10 and the flange 9.

The gaseous fuel entering the head is also conducted between and past the two rearmost tubular necks 10 to discharge into the central zone 13 of the head and to impinge the foremost neck 10 which aligns with the axis of the manifold tube.

The gas delivered to the hollow hub-like central zone of the head is thereafter caused to travel substantially radially outwardly and forwardly through the restricted passageways 14 of the hollow spoke-like portions of the head to be delivered to the two expansion chambers 15 at the front of the head.

The gas expands circumferentially in opposite directions from these expansion chambers into the hollow rim 12 with a portion thereof traveling rearwardly and passing behind the rearmost tubular necks 10 and other portions traveling forwardly to pass ahead of the forward tubular neck 10.

The result of introducing the gaseous fuel directly into the rear expansion chamber 15 and

at the same time to the central zone of the head for distribution through the passages 14 formed by the hollow spokes is to create a substantially uniform gas pressure inside the hollow interior 5 of the rim 12 from which the gas issues to burn in a flame of uniform height at the upper peripheral portion of the head through a peripheral port arrangement generally designated 22.

The peripheral discharge port arrangement is provided by relatively narrow spaces 23 between the adjacent marginal edge portions of the flange 9 and the marginal edge portions of the upper head forming member 7. At circumferentially spaced points the spaces 23 are enlarged to provide a series of holes 24 about the upper periphery of the head with adjacent holes joined to one another through the narrow slit-like apertures 23, and with the holes and the apertures all leading to the hollow interior of the rim.

Secondary combustion air ducts or tubes 25 have their upper discharge ends disposed centrally in the enlarged holes 24 but spaced from the walls of said holes so as to define substantially ring-like discharge ports through which gas in the hollow interior of the rim may issue to burn in a flame hollow at its base. These tubes have their lower ends seated in close fitting holes in the lower head forming member in which they may be press fit or otherwise secured and so that their lower ends open through holes 26 to the space beneath the burner head.

Hence, secondary combustion air is free to flow upwardly through the secondary air tubes 25 to be discharged into the hollow bases of flames burning at the ring-like discharge ports 24.

It is also to be observed that the cored holes 11 defined by the tubular necks 10 provide for the passage of secondary combustion air upwardly through the head to its top side so that the flames are fed with secondary combustion air from inside the ring of flame; while secondary combustion air is free to flow up along the outer edge of the burner to provide an external source of air for the ring of flame.

Inasmuch as the narrow slit-like ports 23 are relatively short and the substantially ring-like ports 24 spaced substantially close together about the periphery of the rim, it will be evident that a great increase of port area is obtained over the conventional practice of providing but a single circular narrow discharge port extending continuously about the peripheral portions of the head.

Attention is also directed to the fact that the burner has no ring-like discharge ports at the back thereof adjacent to the junction between the rim 12 and the manifold tube 18 directly over the rear expansion chamber 15. The discharge port at this rear area of the head comprises a relatively long straight slit connecting the ring-like ports 24 lying at opposite sides of the axis of the manifold tube.

Inasmuch as substantially uniform gas pressure obtains within the hollow interior of the rim 12, as previously stated, the flame which extends uninterruptedly about the upper peripheral portion of the head will have substantially uniform height at all portions thereof.

In the Figure 1-3 embodiment of the invention described a cast burner head construction has been illustrated, but the burner design herein concerned also lends itself readily to fabrication from stampings as shown in the Figure 4-7 embodiment of the invention.

The modified burner herein illustrated is sub-

stantially identical to that previously described with the exception that the ring-like discharge ports 24' are not circular but are elongated or of substantially oval shape, although they can be circular if desired.

The burner head is likewise composed of upper and lower head forming members 7' and 8', respectively, but these members are made of stampings having complementary neck portions 10' pressed inwardly therefrom and telescoping together to form the secondary air holes 11, and to provide for joining the head forming members in spaced apart relationship.

In this embodiment also the lower head member is provided with a flange 9' made as a separate band attached to a short upstanding rim 30 on the peripheral edge portion of the lower head forming member. The upper free edge of the band 9' likewise cooperates with the peripheral edge portions of the upper head forming member 7' to provide the alternate narrow and enlarged apertures as in the previous embodiment.

The secondary air ducts 25', however, are anchored to the bottom head forming member 8' by being pressed into holes 31 formed in a horizontal edge portion of the lower head member.

The secondary air tubes 25' are pressed or brazed into these holes and it will be noted that in the Figure 5 embodiment these tubes curve outwardly toward their upper ends so that the ported surface of the head lies at an outward and downward angle.

The depression 16' of one of the spokes on the bottom of the head forming member 8' is extended rearwardly beyond the rear edge of the head and formed to provide the lower half of the manifold tube 18' and to mate with the upper half of the tube which, as shown, is carried by and formed as a part of the rim flange 9'.

Near its junction with the head, the manifold tube 18' is provided with an enlargement 33 defining a shoulder 34 facing the rim of the head. The shoulder 34 acts as a stop to locate a flame arrester 35 located in the inner end portion of the manifold tube into which it is placed before the mating sections are assembled. The flame arrester 35 may be of any desired design and its function is well known to those skilled in the art and further description thereof is deemed unnecessary.

In the modification shown in Figure 7 the lower head forming member is provided with a peripheral portion lying at an outward and downward angle as in the Figure 2 embodiment so that straight sided secondary air tubes 25'' may be pressed in suitable apertures therein to extend at an upwardly and outwardly diverging angle producing a desirable projection of the flame.

One highly important feature of the fabricated burner of Figures 4 to 7 and which renders the same commercially successful, resides in the fact that all of the joints J between the various stampings from which the burner is made are brazed and have their mouths M lying in parallel planes. This enables use of simple overlapping joints if desired and facilitates disposition of brazing wire into the mouths M of the joints. The brazing of all the joints is accomplished simultaneously by disposing the assembled burner in a brazing oven with the mouths M of all of the mating joints lying in a horizontal condition in which the brazing material is prevented from flowing lengthwise along the joints in an objectionable manner, as would inevitably occur with joints lying at an angle to the horizontal.

Thus uniform penetration of brazing material into the joints is assured.

In all embodiments of the invention, it is also highly important from the standpoint of scavenging the interior of the burner when the supply of fuel is shut off that both the upper and lower head forming members be concave or saucer-shaped, as shown, with their hollow sides facing upwardly. Hence all fuel in the hollow center portion of the head at the time the fuel supply to the burner is shut off flows smoothly outwardly and upwardly to discharge through the peripheral port arrangement with little or no interference from the necks 10.

The objectionable "popping" of the burner at shut-off time is thus eliminated, as the readily escaping fuel continues to burn smoothly until all gas is exhausted from the head.

From the foregoing description taken in connection with the accompanying drawings, it will be readily apparent to those skilled in the art that this invention provides a highly improved burner construction in which the port area is greatly increased and which readily lends itself to cast construction or to fabrication from stampings.

What I claim as my invention is:

1. A gas burner, comprising: a hollow relatively flat burner head having a rim-like periphery; a plurality of apertures in the top wall of the head adjacent to said rim-like periphery thereof adapted to provide discharge ports through which gas admitted to the interior of the head issues to burn as a flame; and hollow secondary air tubes carried by said head adjacent to said rim-like periphery thereof with their lower ends seated and closely fitting in holes in the bottom wall of the head and their upper ends disposed substantially centrally in said apertures but spaced from the sides of said apertures so as to cooperate therewith in the provision of substantially ring-like discharge ports for the burner, said secondary air tubes being adapted to conduct air from beneath the head upwardly through its hollow interior for discharge into the hollow bases of flames burning at said ring-like ports; and said top wall of the head having relatively narrow slits extending entirely therethrough and joining adjacent apertures so as to provide discharge means extending continuously around the top of the head.

2. A gas burner comprising: superimposed disc-like stampings; means joining said stampings together in spaced apart relationship; a band extending about the peripheral portions of said superimposed stampings with its upper marginal edge adjacent to but spaced slightly from the periphery of the upper disc-like stamping; means joining the lower edge of said band and the peripheral edge portion of the lower stamping; cooperating stamped extensions projecting outwardly from the lower stamping and said band providing a manifold tube by which a gas and air mixture may be delivered to the space between said superimposed stampings to issue from the space defined between the upper edge of the band and the peripheral edge portions of the upper disc-like stamping; and a joint between adjacent edge portions of said manifold extensions.

3. The structure set forth in claim 2 wherein all of said joints are brazed and have their mouths accessible at the exterior of the burner and lying in planes parallel to one another to allow disposition of the burner in a brazing oven with the

mouths of the joints in horizontal planes to assure uniform penetration of brazing material into the joints.

4. A gas burner of the character described, comprising: a hollow head including spaced top and bottom head forming members; a substantially upstanding flange on the bottom head forming member extending upwardly and having a substantially scalloped upper edge disposed adjacent to the peripheral edge of the upper head forming member to provide alternate narrow and wide discharge openings about the periphery of the head; and a number of secondary air supply ducts, one for each of said wide discharge openings, seated in close fitting apertures in the lower head member so as to open to the space beneath the head, and each having its upper end centrally located in one of said wide discharge openings but spaced from the walls of said openings to define substantially ring-like discharge ports connected by narrow slit-like ports through which gas in the head issues to burn in a flame.

5. A gas burner, comprising: superimposed disc-like stampings; cooperating means on said stampings for joining the same together in spaced apart relationship and including wall portions extending across said space between the stampings for breaking up said space into a plurality of distributing passages communicating with one another at the center space between the stampings and extending radially outwardly in different directions from said center space, one of said passages providing an inlet through which fuel flows into the burner; a band extending about the peripheral portions of said superimposed stampings; a connection between the lower edge of said band and the peripheral edge of the lower stamping, the upper edge of the band having portions adjacent to but spaced from the peripheral edge of the upper stamping so as to define a discharge port through which gas admitted to the space between said stampings issues to be burned in a flame; and cooperating stamped extensions projecting outwardly from the lower stamping and said band, in line with said inlet passage, to provide a manifold tube through which gas is directly admitted to the ported portion at the outer end of the inlet passage and to the center space between said stampings, the lower stamping having a depression in line with its extension defining the bottom of said inlet passage and leading inwardly to said center space between the stampings to insure gas entering said center space for outward diversion through the remaining passages, thereby enabling even distribution of such gas to the discharge ports.

6. A gas burner, comprising: a relatively flat substantially hollow burner head; inner port forming members on the head spaced about the periphery thereof; cooperating outer port forming members on the head substantially embracing said inner port forming members and spaced therefrom to coat therewith in defining a multiplicity of substantially ring-like ports through which gas delivered to the hollow interior of the head issues to burn in a flame hollow at its base; and means on the outer port forming members between adjacent inner port forming members defining relatively narrow slit-like discharge ports extending entirely through the head and connecting said ring-like ports, and through which gas in the head issues to burn in a substantially flat flame joining the sides of said hollow flames.

7. A gas burner of the character described, comprising: a head including an upper head member, a lower head member, and means joining said head members together in spaced apart relationship comprising a plurality of tubular necks extending between said members and spaced from one another to define a number of distributing passages therebetween leading outwardly from a central zone of the head, said necks also providing holes through the head for unrestricted passage of secondary combustion air upwardly through the burner head from beneath the same; a multiplicity of ducts having their lower end portions anchored in the lower head member to open to the space beneath the head and having their upper ends opening through apertures in the upper head member larger than the upper extremities of the ducts to thereby provide substantially ring-like discharge ports for the heads surrounding the upper extremities of the ducts through which gas fed to the interior of the head issues to burn in flames hollow at their bases with said flames supplied with secondary combustion air through the ducts leading to the interior of the flames; and means on said head defining a manifold tube leading to the interior of the head, the inner end portion of said manifold tube extending partly beneath the lower head member and being in direct communication with the space between said head members and with one of said distributing passages to assure gas delivered to the head entering the same substantially simultaneously at said central zone of the head and at the periphery of the head adjacent to the outer end of said designated distributing passage for uniform distribution in all directions toward the discharge ports; and relatively narrow slits extending entirely through said top head member, and connecting adjacent ring-like ports with one another, and from which gas in the head issues to burn in a relatively flat flame.

8. A gas burner of the character described comprising: a manifold tube; a hollow burner head including upper and lower disc-like head forming members joined together in spaced apart relationship, the lower disc-like member being formed with an outwardly depressed portion leading rearwardly to the edge of the head from a central zone of the head; a connection between the manifold tube and the rear edge of the head disposing the manifold tube in alignment with said depressed portion of the lower head forming member so that said depressed portion acts as an inward continuation of the lower portion of the manifold tube whereby a gaseous fuel flowing through the manifold tube may be delivered substantially simultaneously to said central zone in the interior of the head and to the interior of the head at the rear thereof; a plurality of obstructions in the hollow interior of the head positioned to be impinged by gas entering the head for effecting substantially uniform distribution of the fuel outwardly in different directions from said central zone and toward the edge portions of the head, one of said obstructions being positioned forwardly of said central zone of the head and in line with the manifold tube so as to prevent direct flow of fuel to the front edge of the burner head; cooperating jet forming elements on said head defining substantially circumferentially spaced enlarged apertures opening to the top edge portion of the head joined by relatively narrow slits extending entirely through the top member of

the burner head with said slits and apertures being arranged alternately and continuously about the upper edge portion of the head; and secondary air supply ducts seated in close fitting holes in the lower head forming member beneath said enlarged apertures and leading upwardly through the head to have their discharge ends located centrally in said enlarged apertures but spaced from the walls of the apertures so that said walls of the apertures and the exteriors of the ducts at their discharge ends produce substantially narrow discharge ports encircling the discharge ends of said ducts with said ports spaced from one another about the edge of the head and joined with one another by said narrow slits.

9. In a gas burner of the character described: a burner head having a hollow central portion and a hollow rim surrounding said central portion; means defining a substantially radial inlet fuel passage in the head, the inner end of said passage terminating at the central portion of the head and the outer end thereof opening through and communicating with the rim at the rear edge of the head; means on said rim defining a peripheral port arrangement through which a gaseous fuel admitted into the rim issues to burn in a flame; a manifold tube joined to the rim at the rear of the head and in line with said passage to constitute an outward continuation of the latter, whereby the tube conducts fuel directly to the rim at the rear of the head, and also conducts fuel directly to the central portion of the

head; and means defining other substantially radial diverting passages in the head communicating with the inner terminus of said first designated passage with their axes substantially cross-wise of the axis of said first designated passage for directing all of the fuel brought to said central portion of the head toward circumferentially spaced portions of the rim near the front of the head.
